FOUNDRY SKIMMER

Thomas L. Adas, Chicago, Ill., assignor to
Chicago Railway Equipment Company, Chi-
cago, Ill., a corporation of Illinois

Application January 6, 1939, Serial No. 249,581

6 Claims. (Cl. 266—37)

My invention relates to tools such as skimmers, spoons, rabbling bars or puddle bars for manipulating the plastic iron on the hearth of a puddling furnace or for removing slag from a bath of molten metal. More particularly the invention relates to tools of this type having water cooled structure and the main object of the invention is to combine a water cooled handle and mounting for a blade or bar so that the latter may be discarded and replaced as it burns down without replacing or disassembling the relatively expensive handle structure with its water circulating parts.

This and other detailed objects of my invention are attained by the structure illustrated in the accompanying drawing in which—

Figure 1 is a top plan view of an improved skimmer embodying the invention.

Figure 2 is a horizontal sectional view taken on the line 2—2 of Figure 1 and drawn on a larger scale.

Figure 3 is a vertical section through the head, taken on the line 3—3 of Figure 2.

Figures 4, 5, 6 and 7 are detailed vertical transverse sections taken on the corresponding section lines of Figure 2.

The tool includes a skimming blade 1 and a handle therefor including an elongated annulus 2 with a blade mounting 3 at one end and a manipulating hand-hold 4 at the other end. Blade 1 comprises a solid plate or bar with an opening intermediate its ends, preferably of non-circular contour to receive a nose 5, of smaller contour, on the mounting member 3. The hand-hold 4 is simply a short length of pipe seated in lugs 6 projecting from an L 7 receiving one end of the annulus 2.

Annulus 2 comprises outer and inner tubes 8 and 9 respectively and of substantially different diameters so that a passageway 10 is formed between them. The right hand end of tube 9 is supported by a collar 11 seated in tube 8 and sealing the inner end of passageway 10.

Mounting member 3 has a cup like body portion 12 which fits over tube 8. The bottom of cup like portion 3 merges with the relatively smaller nose portion 5. The interior of member 3 includes a cruciform baffle structure comprising vertical vanes 13 and horizontal vanes 14. The inner ends of these vanes mount the left hand end of tube 9. Vanes 13 terminate adjacent the bottom of portion 12 of the mounting member but vanes 14 project into the hollow interior of nose portion 5 but terminate short of the outer end of the latter.

Tube 8 is provided with a threaded nipple 16 for connection to a water supply line and L 7 is threaded for connection to a discharge line. Water, or other cooling fluid, entering nipple 16 passes along the exterior of tube 9 to the extreme outer end of nose 5 and then inwardly of tube 9 to the outlet in L 7. The baffles insure the circulation of the fluid and the elimination of any pockets in which steam or vapor may collect and interfere with the substantial uniform cooling of 10 the annulus and particularly of the mounting member 3.

Bar 1 is retained in position on member 3 by a cap nut 17. If this nut is screwed down tightly when the bar is first mounted the subsequent expansion of the parts when heated will form such tight joints that there will be no crevices to admit molten metal under ferrostatic pressure and injure the threads on nose 5 or permit fusing of the metal itself in the joints.

The circulation of cooling fluid to the extreme forward end of nose 5 maintains even nut 17 sufficiently cool to avoid welding same to nose 5 and bar 1 and when the bar has burned down to such an extent that it is no longer serviceable nut 17 and what remains of bar 1 may be removed from mounting 3 and a new bar applied.

Tube 9 is unsupported intermediate collar 11 and the supporting baffle structure and the cooling liquid may circulate freely throughout the 30 length of passageway 10. The outer tube 8 first receives the cooling fluid and therefore its temperature is maintained at a lower level than would be the case if the fluid was first received in the inner tube, and as the fluid is admitted 35 under a substantial pressure, at least 15 lbs., any steam or vapor formed in the device will tend to take the path of least resistance which would lead to the outlet in L 7.

It will be understood that the annulus, including the end member 3 with its baffle structure may be used to mount ladles, spoons or accessories other than the skimmer blade or the annulus may be used as a rabbling or puddling bar or agitating stick independently of any accessories. 45 These and other variations in the details of the structure may be made without departing from the spirit of the invention and the exclusive use of such modifications as come within the scope of the claims is contemplated.

What is claimed is:

1. In a tool of the class described for skimming molten metal, elongated outer and inner tubes forming an annular passageway between them, a separately-formed, relatively heavy and 55

- short cup like terminal member surrounding and receiving the end of said outer tube and including a cruciform vane structure extending into and mounting said inner tube and providing for the flow of cooling fluid from said passageway throughout the interior of said terminal member and then into said inner tube to a discharge point remote from said member, and a skimming blade mounted on said member independently of the fluid passageways.
2. In a hand manipulated tool for skimming molten metal, an elongated handle comprising substantial lengths of ordinary tubing, one within the other and forming an annulus arranged for circulation of cooling liquid to the extreme end thereof and including a relatively short heavy separately-formed external threaded hollow liquid-receiving terminal member providing for the return of liquid through the handle, a detachable bar apertured to receive said member, and a nut on said member detachably securing said bar thereto.
3. In a tool for skimming molten metal, a solid head, a handle including inner and outer tubes forming an annulus and including an end portion extending through and mounting said head, and baffle vanes in said end portion and extending longitudinally thereof and arranged at angles to each other, said vanes extending into said inner tube to mount the latter and one of said vanes extending beyond the end of said tubes towards the opposite end of said head, and the other of said vanes terminating short of said head.
4. In a tool for skimming molten metal, inner and outer tubes forming an annulus, a cup-like terminal mounted on said outer tube and having a hollow nose portion of restricted diameter pro-

jecting outwardly from its bottom wall and exteriorly threaded, vane elements integral with said member and projecting into said nose portion and into said inner tube to mount the latter in spaced relation to said outer tube, a solid head apertured to receive said nose portion and seated against the shouldered bottom of the cup like terminal, and a nut threaded onto said nose portion and thrusting said head against its seat.

5. In a tool of the class described for skimming molten metal, an outer tube and an inner tube forming an annular passageway between them, a hollow terminal member surrounding and seating an end of said outer tube and having elements extending into and supporting the end of said inner tube and providing for the flow of fluid from said passageway to the end of said member and then into said inner tube, a solid skimmer blade having an aperture to receive said member to mount the blade thereon independently of the fluid retaining elements of the tool, and means detachably securing said blade to said member.

6. In a tool of the class described for skimming molten metal, an outer tube and an inner tube forming an annular passageway between them, a hollow terminal member surrounding and seating an end of said outer tube and having elements extending into and supporting the end of said inner tube and providing for the flow of fluid from said passageway to the end of said member and then into said inner tube, a solid skimmer blade having an aperture to receive said member, and releasable means holding said blade on said member, said means permitting removal of said blade from said member without disassembling said member and either of said tubes.

THOMAS L. ADAS.
